SLIPPER

Florence B. Zacks, Columbus, Ohio, assignor to R. G. Barry Corporation, Columbus, Ohio, a corporation of Ohio

Filed July 9, 1962, Ser. No. 70,852

Term of patent 14 years

(Cl. D7—7)

FIGURE 3 is a perspective view of the slipper of my new design, the conventional sole being depicted in broken lines.

The dominant feature of my design resides in the specific embroidered floral element shown in detail on the drawing.

I claim:

The ornamental design for a slipper, as shown and described.
